US00D449321B1

(12) **United States Design Patent** (10) Patent No.: **US D449,321 S**
Su (45) Date of Patent: ** Oct. 16, 2001

(54) **OPTICAL LENS WITH A TAIL**

- (75) Inventor: **Kai C. Su**, Alpharetta, GA (US)
(73) Assignee: **Technology Resource International Corporation**, Alpharetta, GA (US)
(**) Term: **14 Years**
(21) Appl. No.: **29/115,010**
(22) Filed: **Dec. 6, 1999**
